SOAP HOLDING BRUSH

William Novick, Brooklyn, N. Y.

Application December 22, 1945, Serial No. 636,856

2 Claims. (Cl. 15—222)

1

This invention relates to a cleaning device, and more particularly to new and useful improvements in a soap and sponge holding brush.

The present invention proposes new construction of a soap and sponge holding brush having bristles positioned in close proximity to the brush opening and soap and sponge gripping means of novel design.

An object of the invention is to increase the effectiveness of the device by providing long, silky bristles close to the soap and sponge compartment to cooperate in the lathering operation, and by providing shorter, stiffer bristles near the ends of the brush to cooperate in the scrubbing operation.

Another object is to provide a basket that can be inserted easily in the brush opening, and co-acting means to retain it in functioning position.

A further object is to provide the basket with resilient mesh to cooperate with a gripping means to hold the soap and sponge firmly.

Still another object is to provide a new gripping means activated by springs to maintain a firm grip on the soap and sponge as they change in size and hardness while in use.

A further object is to provide a gripping means having a plate with a large gripping surface and openings therethrough.

Another object is to provide a brush with new construction within its opening to contain the basket, soap, sponge and gripping means.

A further object is to provide a cover for the brush having means on its undersurface to retain the gripping means in functioning position, the gripping means in turn cooperating to secure the cover firmly to the brush.

Another object is to provide the cover with openings which together with the openings in the lower plate of the gripping means permit water, suds and air to circulate freely through the brush opening thus ensuring efficiency while in use and adequate drainage at other times to keep the brush and its parts fresh, clean and dry.

Other objects are to provide a brush of the class specified that is sturdy in construction, easy to load, unload and clean, efficient in operation, and cheap in cost.

These and other objects are accomplished by providing a cleaning device comprised of a bristled brush, a cover, a meshed basket, gripping means and a strap. The brush has an opening therethrough in which a cake of soap, a sponge, the basket and the gripping means are positioned. The cover can be slid along the top of the brush securing them together and fixing the gripping

2

means in position. The gripping means has a spring which acts on a plate holding the soap and sponge firmly against the mesh of the basket, and the strap is detachably secured to the brush.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a cleaning device embodying the invention herein and being used by a person indicated diagrammatically.

Fig. 2 is another perspective view of the device showing its top and sides in more detail.

Fig. 3 is a bottom view of the central portion of the device showing an opening in the brush, a mesh thereacross, and bristles positioned closely about the opening.

Fig. 4 is a perspective view of the body part of the brush broken away to reveal the structure.

Fig. 5 is a perspective view of the meshed basket used in the device.

Fig. 6 is a perspective view of the cover portion of the device.

Fig. 7 is a perspective view of the gripping means used in the device.

Fig. 8 is a section along the line 8—8 of Fig. 2.

Fig. 9 is a section along the line 9—9 of Fig. 2.

Fig. 10 is a cross section of a variation of the invention, the section being along a line corresponding to 8—8 of Fig. 2.

Fig. 11 is a perspective view of a modified gripping means used in the device shown in Fig. 10.

In the drawings and in the specification, in which like reference numbers designate similar parts, the cleaning device 11^a shown in Figs. 1 to 9 inclusive, is comprised of a brush 12, a basket 13, a detachable cover 14, gripping means 15 and two straps 16.

The brush 12 has a body portion 17 having an opening 18 extending therethrough from its top to its bottom. Bristles 19 are secured in orifices in the bottom of the body portion and are positioned closely about the opening 18. They vary in length and texture from comparatively long

50 and silky bristles 20 adjacent to the opening to perform the lathering function of the brush, to comparatively short and stiff bristles 21 near the ends of the brush removed from the opening to perform the scrubbing function of the brush (see 55 Fig. 8). The brush body 17 has sloping shoulders

22 on either side of its central portion to compensate for the change in length of the bristles, the ends of the bristles being in one plane. The brush body can be made of wood or plastic, and can also be made without the sloping shoulders permitting the bristle ends to form a brush with a rounded bottom.

The basket 13 (see Fig. 5) consists of a frame 23 which can be made of plastic, metal, or plastic coated metal, and a resilient mesh 24 attached to the frame. The mesh can be made of a strong, smooth, flexible thread, such as nylon or a suitably coated wire. The frame 23 has flanges 25 extending along each of its sides which coat with and rest on shoulders 26 in the brush opening 18 with the mesh 24 extending along the opening at the bottom of the brush at approximately the same level as the ends of the bristles. The basket 13 can be permanently secured to the brush body in functioning position or can be removable, and is capable of containing a cake of soap 27 and a sponge 28.

The detachable cover 14 (see Fig. 6) has two opposite edges bent over to form sockets 29 capable of admitting and slideably engaging flanges 30 on top of the brush body 17. The flanges 30 extend along opposite sides of the opening 18 forming tracks so that the cover can be slid along the top of the brush with the flanges 30 in the sockets 29 to close the top of the opening. The cover 14 can also be detachably secured to the brush top by a dovetail or similar interlocking joint which permits movement in only the desired direction. The bottom surface of the cover is provided with two slats 31 positioned centrally between the sockets 29, the slats being spaced apart to form a way 32 between them which is parallel to the sockets and extends along the length of the cover. The function of the way 32 will presently appear in the description of the gripping means 15. Openings 33 extending through the cover 14 permit full drainage of the brush opening 18 and allow the air to circulate freely therethrough to keep the device fresh and dry when not in use.

The gripping means 15 (see Fig. 7) is positioned in the brush opening 18 and acts on the soap and sponge to hold them firmly against the resilient mesh 24. The gripping means 15 consists of an upper plate 34 and a larger lower plate 35 joined by or integral with spring members 36. The upper plate 34 has a guide or slat 37 on its outer face adapted to fit slidably in the way 32 in the cover 14, and the lower plate 35 has a plurality of openings 38 to permit water and air to pass freely through the opening 18. The spring members 36 curve inwardly and act to keep the plates apart and to hold the soap and sponge firmly between the mesh and the lower gripping plate.

The straps 16 are removably secured to the brush shoulders 22 by coacting interlocking tongue and groove means 39.

The cleaning device 11a is assembled as follows: The basket 13 is inserted into the brush opening 18 through the top of the brush and is positioned with its flanges 25 resting on the shoulders 26 in opening, whereupon the mesh 24 will extend across the opening at the bottom of the brush. The soap 27 and sponge 28 are then placed in the basket with either the soap or sponge adjacent to the mesh, as desired. The gripping means 15 is then placed in the opening with its perforated lower plate 35 in contact with the topmost of the soap and sponge. The upper

plate 34 is then depressed against the action of the spring members 36 until the slat 37 on the upper plate is almost flush with the top surface of the brush body 17. The cover 14 is then slid along the top of the brush until the opening 18 is covered, the sockets 29 engaging the flanges 30 on the brush, and the way 32 admitting the slat 37 of the upper plate (see Figs. 8 and 9). As the soap is used up, the spring members 36 will continue to grip the soap and sponge securely.

In the variation of the invention shown in Figs. 10 and 11, the cleaning device 40 has a modified gripping means 41 comprised of an upper plate 42 and a lower plate 43 joined by two spiral springs 44 positioned in seats 44a in the plates and acting to keep them apart when they are forced toward each other. The upper plate 42 is provided with a slat 45 having dovetailed sides 46. A cover 47 for the brush has two slats 48 on its undersurface spaced apart and with sides forming a mortise for the dovetailed slat 45 on the upper plate 42. In other respects, the cleaning device 40 is similar to the device 11a and can be loaded in the manner hereinabove described.

Although the gripping means described in the devices utilize in one case arcuate spring members between the plates, and in the other case coil springs, any other type of spring can be used in any number positioned between the plates and acting to keep them apart when pressed toward each other and to retain the soap and sponge in an advanced position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A cleaning device for use with a cake of soap, the device being comprised of a brush, a meshed basket, a cover, interlocking means, a sponge, and gripping means, the brush having an opening therethrough capable of containing the basket, soap, sponge and gripping means, and being further provided with a shoulder within the opening, the brush bristles extending closely about the opening at the bottom of the brush and varying in length and texture from comparatively long and silky bristles adjacent to the opening to comparatively short and stiff bristles near the ends of the brush removed from the opening, the cover being detachably secured to the top of the brush by the coacting tongue and groove interlocking means, and the bottom of the cover having a way to retain the gripping means in position, the basket having a flange and being positioned within the opening with the flange resting on and co-acting with the shoulder within the opening, and with the mesh of the basket extending across the opening at the bottom of the brush, and the gripping means comprising a lower gripping plate, a spring, and an upper plate having a slat adapted to fit slidably in the way on the bottom of the cover, the gripping means being positioned within the brush opening with its spring between its plates and acting to force them apart when they are pressed toward each other, said sponge being disposed intermediate said soap and said lower gripping plate whereby

said sponge is retained in position under compression exerted by said gripping means.

2. A cleaning device for use with a cake of soap the cleaning device comprising a brush, a cover, a meshed basket, gripping means, a sponge, and strap, the brush having an opening therethrough capable of containing the basket, soap, sponge, and gripping means, and being further provided with a shoulder within the opening, the brush bristles extending closely about the opening at the bottom of the brush and varying in length and texture from comparatively long and silky bristles adjacent to the opening to comparatively short and stiff bristles near the ends of the brush removed from the opening, the brush and cover having coacting tongue and groove interlocking means for detachably securing them together, whereby the cover can be slid across the top of the brush closing the opening, the basket having a flange and being positioned within the opening with the flange resting on the shoulder within the opening, and with its mesh

extending across the opening at the bottom of the brush, the gripping means comprising a gripping plate resiliently mounted on said device and positioned within the brush opening with the gripping plate engaging said sponge, said sponge being positioned intermediate said gripping plate and said soap, whereby the soap and sponge are firmly held in position between the basket mesh and the plate.
